Primary Examiner — Rosemary K Tarcza(74) *Attorney, Agent, or Firm* — Wood, Herron & Evans,
LLP(57) **CLAIM**

The ornamental design for a battery pack for hand held electrical device, as shown and described.

DESCRIPTION

FIG. 1 is a front isometric view of the battery pack for hand held electrical device with a hand held light shown in broken lines, which forms no part of the invention, to illustrate environment;

FIG. 2 is a front isometric view of the battery pack for hand held electrical device;

FIG. 3 is a rear isometric view thereof;

FIG. 4 is a front elevational view thereof;

FIG. 5 is a right side elevational view thereof;

FIG. 6 is a left side elevational view thereof;

FIG. 7 is a rear elevational view thereof;

FIG. 8 is a top plan view thereof; and,

FIG. 9 is a bottom plan view thereof.

The features shown in broken lines are for illustrative purposes only and form no part of the claimed design.
